(57) **CLAIM**

The ornamental design for a filter housing, as shown and described.

DESCRIPTION

FIG. 1 is a perspective view of a filter housing according to the invention;

FIG. 2 is a front view of the filter housing of FIG. 1;

FIG. 3 is a left side view of the filter housing of FIG. 1;

FIG. 4 is a rear view of the filter housing of FIG. 1;

FIG. 5 is a right side view of the filter housing of FIG. 1;

FIG. 6 is a top view of the filter housing of FIG. 1; and,

FIG. 7 is a bottom view of the filter housing of FIG. 1.

The filter housing characterized in that at least a portion of the surface below the horizontal bar shown in FIGS. 1, 3 and 5 is translucent.

The broken line showing of the environment is for illustrative purposes only and forms no part of the claimed design.
